EXTRACTION PROCESS

Mott Souders, Jr., Piedmont, Calif., assignor to
 Shell Development Company, San Francisco,
 Calif., a corporation of Delaware

Application November 3, 1942, Serial No. 464,403

6 Claims. (Cl. 183—115)

This invention relates to the separation of hydrocarbon mixtures of narrow boiling range which are difficultly separable by ordinary fractionation. More particularly, the invention relates to the separation of narrow boiling hydrocarbon mixtures containing two or more components of different degrees of saturation. The invention is especially valuable in connection with the separation of olefins of four carbon atoms from normal butane and as so applied constitutes an improvement on the process described in copending application Serial No. 332,366, which issued as Patent No. 2,371,908 on March 20, 1945.

In the process of the above-identified copending application, mixtures of olefins and paraffins or mono-olefins and diolefins are separated by contacting them with an aqueous organic solvent, the organic constituent of which may be acetone, for example, to selectively dissolve the more unsaturated component which is obtained as a highly purified material upon subsequent regeneration of the solvent solution as by distillation. The process is conveniently executed by passing the mixture to be separated in counter-current relation to the aqueous solvent in a column provided with suitable contact and/or distributing elements, as plates, spiders, baffles; etc., the solvent being introduced into the column at a point above the point of introduction of the feed mixture. The solution containing the dissolved olefin is withdrawn from the bottom of the column while the undissolved portion of the treated mixture is recovered as overhead.

Application of the foregoing process as executed with a solvent consisting of water and acetone to the treatment of mixtures of olefins of four carbon atoms as normal butylenes and isobutylene with normal butane has given rise to considerable operating difficulty because of loss of acetone with the overhead vapors. This is believed to result, partially at least, from the formation of an azeotrope of normal butane and acetone, since the difficulty is not corrected by the employment of additional rectifying plates between the solvent inlet port and the top of the column. By means of such rectifying or "knockdown" plates it is sometimes possible in distillation or extraction processes of the type involved to prevent any substantial loss of solvent with the overhead, but this expedient has been found valueless as to mixtures containing normal butane.

A further operating difficulty, experienced not

only during the treatment of mixtures containing normal butane but also during the treatment of mixtures free of this hydrocarbon, results from the accumulation in the aqueous organic solvent of hydrocarbons of a higher molecular weight than the hydrocarbons in the mixture being separated. Mixtures of the type subjected to the treatment according to the process of application, Serial No. 332,366, are obtained, for example, by the pyrolysis of petroleum or petroleum fractions. Although by ordinary fractionation it is relatively easy to obtain cuts or fractions from the pyrolyzed product which predominate in hydrocarbons of 5 the same number of carbon atoms, it is practically impossible to achieve absolutely clean separation. Thus, a C₄ hydrocarbon cut will invariably be contaminated with at least minor amounts of amylanes, pentanes, pentadienes, etc. 10 Upon subsequent continuous extraction of the C₄ fraction these higher molecular weight hydrocarbons tend to build up in the solvent with a consequent adverse effect upon its efficiency. 15 A principal object of the present invention is to provide an improved process for effecting the recovery of acetone from the overhead produced when a mixture comprising one or more olefins together with one or more paraffins, particularly a mixture comprising one or more olefins of 20 four carbon atoms together with normal butane, is extracted with an aqueous acetone solvent. Another object is to effect continuous recovery of the acetone content of the overhead in a manner providing for its immediate recirculation. Still 25 another object is to provide an improved process for separating olefins from paraffins by means of an aqueous acetone solvent wherein the lean or regenerated solvent produced incident to the recovery of the extracted olefin is continuously 30 or intermittently freed of undesirable hydrocarbon accumulate. A still further object is to provide an improved process which is generally applicable to the separation of narrow boiling hydrocarbon mixtures containing components of 35 different degrees of saturation as mixtures of mono-olefins and diolefins, mono-olefins and/or diolefins and paraffins, etc.

According to the present invention, as carried out using an aqueous solution of acetone as the 40 selective solvent, the acetone-containing overhead vapors from the extraction column are condensed with the formation of two liquid phases. The upper or hydrocarbon phase is returned to the extraction column as reflux, while 45 the lower phase, which is relatively richer in 55

acetone, is introduced into a scrubbing zone, which may conveniently be a second column or tower, wherein it is scrubbed with water. The acetone solution obtained through the scrubbing operation is separated from the undissolved component or components and conveyed to a distillation unit which is operated under such conditions as to produce an aqueous acetone solution of a strength equivalent to that of the solution being employed in the extraction tower. The aqueous acetone solution so produced may be returned to the extraction tower either directly or from intermediate storage.

In the execution of the invention using aqueous acetone as the selective solvent, water washing is also employed to effect the removal of the undesirable hydrocarbon accumulate from the regenerated solvent produced upon distillation of the olefin solution from the extraction column. According to one embodiment of the invention the water washing of the regenerated or lean solvent is carried out in the same scrubbing zone into which the acetone rich phase of the extraction column overhead is introduced.

The invention will be more clearly understood from the following detailed description and the accompanying flow diagrams illustrative of methods of applying it. Figure I represents a system adapted especially to the separation of mixtures of normal butane and other hydrocarbons of four carbon atoms having a lesser degree of saturation by means of an aqueous acetone solvent. Figure II represents a modification of this system. The drawings indicate only the essential and/or desirable apparatus elements and their relation to each other, minor elements such as pumps, compressors, valves, and the like being in the main omitted. Proper placement of these auxiliaries will at once be evident to those skilled in the art to which the invention pertains.

With reference to Figure I, the numeral 10 denotes an extraction column provided with the heat source shown as a closed heating coil 11 through which may be circulated a heating medium, such as steam, hot oil, and the like. The mixture to be separated, which will be considered as consisting of alpha and beta butylenes, normal butane and isobutane, is introduced into column 10 via line 12 at approximately the point indicated. As the gaseous mixture ascends into the column 10, it is met by a descending stream of an aqueous acetone solution, having an acetone concentration of from about 75 to about 90 percent, introduced into the column 10 via line 13 at a point below the point of introduction of the feed mixture. The olefinic content of the feed mixture is selectively dissolved by the aqueous acetone solvent which has a preferential affinity therefor. Any paraffin hydrocarbon, e. g. butanes, dissolved by the solvent is substantially completely removed therefrom in the lower portion of the column, which is maintained at a relatively higher temperature than the rest of the column by means of the heating coil 11. The solution of olefins in the aqueous acetone solvent is conveyed from column 10 through line 14 to stripping column 15, which is provided with a heat source 16 also indicated as a closed heating coil. Column 15 is operated at a temperature sufficient to remove the dissolved olefins which are recovered as overhead. The stripped or lean solvent is withdrawn from column 15 through line 17 which communicates with solvent feed line 13 as shown.

The top or overhead product from extraction

column 10 consisting of the butanes present in the original mixture plus acetone is conveyed through an overhead vapor line 18 to a condenser and phase separator 19. Two liquid layers are formed in condenser 19. Each layer contains both acetone and paraffin hydrocarbon but the lower layer is relatively richer in acetone than the upper. Controlled quantities of the liquid in the upper layer are preferably returned to the extraction column as reflux via reflux line 20, while the liquid in the lower layer is conveyed through line 21 to a scrubbing tower 22 wherein it is scrubbed with water admitted through line 23. This serves to separate substantially all of the butanes which have only negligible solubility in water. The dilute aqueous acetone solution resulting from the scrubbing operation is withdrawn through line 25 to a concentrating column 26. It should be noted that if desired all of the liquid which accumulates in condenser-separator 19 may be conveyed to tower 22, but best results have been found to follow by operating with reflux as described.

Column 26 shown as equipped with a heat source 27, an overhead vapor line 28, and a condenser 29 is operated to produce an overhead fraction consisting of acetone and water, which fraction has an acetone concentration substantially equivalent to the aqueous acetone solvent being employed in extraction column 10 and a bottom fraction consisting of water. The condensed overhead is withdrawn from condenser 29 through line 30 which communicates with lines 17 and 13 as shown, while the water fraction may be recycled as in the drawing to the scrubbing tower.

As previously herein indicated, it is highly desirable that the solvent recycled to the extraction column 10 be substantially completely free of hydrocarbon material. For the purpose of avoiding the accumulation in the solvent of hydrocarbon material not removed by the stripping operation in column 15, a line 31, which may be called the "regenerated solvent clean-up line," is provided. This line terminates near the bottom of scrubbing column 22.

The rate of take-off or the amount of regenerated solvent withdrawn from line 17 through line 31 and thence to column 22 varies within wide limits, being determined primarily by the purity of the hydrocarbon fraction being separated. This in turn depends upon the source of the fraction, or in the case of cuts derived from pyrolyzed petroleum fractions upon the efficiency of the available prefractionation equipment. In operating upon a butylene-butane fraction separated from a pyrolyzed petroleum fraction with ordinary refinery fractionating equipment, it has been found that the solvent may be maintained in near optimum condition by directing from about $\frac{1}{30}$ to about $\frac{1}{40}$ of the regenerated solvent into line 31. The hydrocarbon material separated from the regenerated solvent withdrawn from line 17 via line 31 is recovered from column 22 as overhead along with the butanes separated from the extraction column overhead.

It should be mentioned that, if desired, all of the regenerated solvent from the stripping column may be water-washed before its re-introduction into the extraction column. The water-washing of either all or a part of the regenerated solvent may be carried out in tower 22 as shown, that is in the same tower in which the overhead from the extraction column is scrubbed or in a second scrubbing tower.

Still further modifications of the invention will immediately suggest themselves. For example, it may be advantageous where it is desired to continuously water-wash all or a large portion of the regenerated solvent prior to its re-use in the extraction column to employ both the column in which the overhead from the extraction column is scrubbed and a second column, the regenerated solvent to be washed being proportioned either equally or otherwise between the two columns. Also, the employment of a second or, for that matter, a third or a still greater number of scrubbing columns or towers may be coupled with water scrubbing of all or a part of the stripping column overhead, that is the overhead from column 15 which, under certain circumstances, may contain sufficient acetone to justify such operation. Thus the system used may approximate the modification disclosed in Figure II wherein like numerals refer to like parts in Figure I.

In Figure II the overhead from stripping column 15 is conveyed via line 32 to a second scrubbing tower or column 33. Water is supplied to column 33 through line 35. A line 36 extends from stripping column exit line 17 to column 33, terminating near the bottom of the column, while a branch line 37 extends from line 36 to the bottom portion of the scrubbing tower 22. Under this arrangement, and assuming of course the incorporation of suitable control valves in the system, any desired amount of the regenerated solvent from the stripping column may be conveyed to either of the two scrubbing towers. The top fraction produced by column 33 consists of the olefins dissolved by the aqueous acetone solvent in the extraction column plus the hydrocarbon accumulate separated from the regenerated solvent by the washing operation. The dilute aqueous acetone solution produced as bottom product may be concentrated to the desired strength for use in the extraction column either in a second concentrating column 38, as shown, to which column it is conveyed by line 39, or, if desired, in column 26. In the latter event column 28 is necessarily of greater capacity than where only the dilute solution from column 22 is concentrated therein.

When operating with a single concentrating column, the bottom products of each of the scrubbers may be combined and introduced into the concentrating column at a single point, while the water fraction constituting the bottom product of the concentrating column may be split in proper proportion between the two scrubbing towers.

If the system comprises the use of a second concentrating column, as shown in the drawings, that is column 38, the concentrated overhead is introduced after condensation into the solvent return line just as in the case of the concentrated overhead from column 26, while the water bottom fraction is recycled to scrubbing tower 33 via line 35.

It is to be understood that execution of the invention may not entail the water scrubbing of the extraction column overhead but only water scrubbing of the overhead from the stripping column 15. In this case columns 22 and 26 may or may not form part of the system.

The improved process of the present invention is advantageous in the two major respects that the solvent employed in the extraction column is completely recovered for re-use and is at the same time maintained in a state of highest operating efficiency. Although especially applicable,

as stated, to the separation of narrow boiling hydrocarbon fractions comprising normal butane, as mixtures of butadiene and/or butylenes with normal butane, it may be applied with equal success to the treatment of other narrow boiling hydrocarbon mixtures as mixtures of ethylene and ethane, propylene and propane, butadiene and butylenes, amylanes and pentadienes, amylanes and/or pentadienes and pentanes, etc.

5 10 The invention is not limited to extraction or distillation operations involving the use of aqueous organic solvents but may be put into effect where the extraction is carried out with an anhydrous solvent having the required degree of selectivity. Nor is it necessary for the solvent to have a greater affinity for the more unsaturated of the components to be separated as the process is applicable where non-polar solvents, such as ether, trichlorethylene, carbon tetrachloride, etc., are used. In non-polar solvents, such as those specifically named, paraffins are relatively more soluble than olefins and mono-olefins are relatively more soluble than diolefins; hence, the more saturated component is extracted rather than the more unsaturated.

15 20 25 Among the many solvents, which like aqueous or anhydrous acetone have a preferential solvent power for the more unsaturated components as between components of different degrees of saturation, may be mentioned: furfural, ethylene chlorhydrin, epichlorhydrin, nitriles, as acetone and propionitriles, dichlorethyl ether, dimethyl glycerol ether, isocrotyl chloride, acid anhydrides, as the anhydrides of acetic and propionic acids, etc.

30 35 40 45 50 When operating with an anhydrous solvent, the solvent concentrating column or columns are of course operated to produce an anhydrous product for recycle. It should also be mentioned that it may be advantageous in some cases to use a liquid other than water as the scrubbing agent to produce the dilute substantially hydrocarbon-free solution or solutions of the solvent. Like water, the liquid used should have relatively little solvent power for hydrocarbons. For example, ethylene glycol, glycerol, trimethylene glycol, ethylene diamine, ethanolamine, etc. may be used in lieu of water when operating with anhydrous acetone.

55 60 65 70 75 I claim as my invention:

1. In a process which comprises contacting a gaseous mixture containing a butylene and normal butane with an aqueous acetone solvent to produce a solution of the butylene in the aqueous acetone solvent, which solution after separation from the residual mixture is subsequently treated to recover the butylene therefrom and to produce a regenerated acetone solvent, the improvement which comprises subjecting the residual mixture to condensation conditions under which two liquid phases are formed, the lower of said phases being relatively richer in acetone than the upper, passing the liquid in the lower phase and at least a part of the regenerated solvent produced upon recovery of the butylene into a scrubbing zone, scrubbing the said liquid and the regenerated solvent passed into said zone with water to separate hydrocarbon material therefrom and to produce a dilute aqueous solution of acetone, concentrating the dilute aqueous solution of acetone to an acetone concentration substantially equivalent to the acetone concentration of the aqueous acetone solvent employed to produce the solution of the butylene, and employing the con-

centrated solution to extract additional quantities of the butylene.

2. In a process which comprises contacting a mixture containing an olefin and a paraffin of similar boiling temperatures and having the same number of carbon atoms per molecule, with an aqueous acetone solvent to produce a solution of the olefin in the aqueous acetone solution, which solution after separation from the residual mixture is subsequently treated to recover the olefin therefrom and to produce a regenerated acetone solvent, the improvement which comprises subjecting the residual mixture to condensation conditions under which two liquid phases are formed, the lower of said phases being relatively richer in acetone than the upper, passing the liquid in the lower phase and at least a part of the regenerated solvent produced upon recovery of the olefin into a scrubbing zone, scrubbing the said liquid and the regenerated solvent passed into said zone with water to separate hydrocarbon material therefrom and to produce a dilute aqueous solution of acetone, concentrating the dilute aqueous solution of acetone to an acetone concentration substantially equivalent to the acetone concentration of the aqueous acetone solvent employed to produce the solution of the olefin, and employing the concentrated solution to extract additional quantities of the olefin.

3. In a process for the separation of a narrow boiling hydrocarbon mixture containing a component of a different degree of saturation but having the same number of carbon atoms as a component from which it is to be separated, which process comprises contacting said hydrocarbon mixture with a selective solvent to produce a solution of the said component in the solvent, which solution after separation from the residual mixture is subsequently treated to recover said hydrocarbon component therefrom and to produce a regenerated solvent, the improvement which comprises subjecting the residual mixture to condensation conditions under which two liquid phases are formed, the lower of said phases being relatively richer in selective solvent than the upper, passing the liquid in the lower phase and at least a part of the regenerated solvent produced upon recovery of the aforementioned hydrocarbon component into a scrubbing zone, scrubbing the said liquid and the regenerated solvent passed into said zone with a liquid having relatively little solvent power for hydrocarbons to produce a diluted substantially hydrocarbon-free solution of the selective solvent, concentrating said diluted solution to substantially the strength of the solvent employed to produce the solution of the said hydrocarbon component, and employing the concentrated solvent to dissolve additional quantities of the said hydrocarbon component.

4. In a process for the separation of a narrow boiling hydrocarbon mixture containing a diolefins and a more saturated hydrocarbon of similar boiling temperature and having the same number of carbon atoms per molecule, with an aqueous acetone solvent to produce a solution of the diolefins in the aqueous acetone solution, which solution after separation from the residual mixture is subsequently treated to recover the diolefins therefrom and to produce a regenerated acetone solvent, the improvement which comprises subject-

ing the residual mixture to condensation conditions under which two liquid phases are formed, the lower of said phases being relatively richer in acetone than the upper, passing the liquid in the lower phase and at least a part of the regenerated solvent produced upon recovery of the diolefins into a scrubbing zone, scrubbing the said liquid and the regenerated solvent passed into said zone with water to separate hydrocarbon material therefrom and to produce a dilute aqueous solution of acetone, concentrating the dilute aqueous solution of acetone to an acetone concentration substantially equivalent to that of the aqueous acetone solvent employed to produce the solution of the diolefins, and employing the concentrated solution to extract additional quantities of the diolefins.

5. In a process which comprises contacting a gaseous mixture containing a butadiene and a butylene with an aqueous acetone solvent to produce a solution of the butadiene in the aqueous acetone solvent, which solution after separation from the residual mixture is subsequently treated to recover the butadiene therefrom and to produce a regenerated acetone solvent, the improvement which comprises subjecting the residual mixture to condensation conditions under which two liquid phases are formed, the lower of said phases being relatively richer in acetone than the upper, passing the liquid in the lower phase and at least a part of the regenerated solvent produced upon recovery of the butadiene into a scrubbing zone, scrubbing the said liquid and the regenerated solvent passed into said zone with water to separate hydrocarbon material therefrom and to produce a dilute aqueous solution of acetone, concentrating the dilute aqueous solution of acetone to an acetone concentration substantially equivalent to that of the aqueous acetone solvent employed to produce the solution of the butadiene, and employing the concentrated solution to extract additional quantities of the butadiene.

6. In a process which comprises contacting a gaseous mixture containing a pentadiene and an amylene with an aqueous acetone solvent to produce a solution of the pentadiene in the aqueous acetone solvent, which solution after separation from the residual mixture is subsequently treated to recover the pentadiene therefrom and to produce a regenerated acetone solvent, the improvement which comprises subjecting the residual mixture to condensation conditions under which two liquid phases are formed, the lower of said phases being relatively richer in acetone than the upper, passing the liquid in the lower phase and at least a part of the regenerated solvent produced upon recovery of the pentadiene into a scrubbing zone, scrubbing the said liquid and the regenerated solvent passed into said zone with water to separate hydrocarbon material therefrom and to produce a dilute aqueous solution of acetone, concentrating the dilute aqueous solution of acetone to an acetone concentration substantially equivalent to that of the aqueous acetone solvent employed to produce the solution of the pentadiene, and employing the concentrated solution to extract additional quantities of the pentadiene.

MOTT SOUDERS, JR.
